(57) **CLAIM**

The ornamental design for a location tag holder as shown and described.

DESCRIPTION

FIG. 1 is a front view of a location tag holder showing my new design;

FIG. 2 is a rear view of the location tag holder;

FIG. 3 is a left side view of the location tag holder;

FIG. 4 is a right side view of the location tag holder;

FIG. 5 is a top view of the location tag holder;

FIG. 6 is a bottom view of the location tag holder;

FIG. 7 is a top front side perspective view of the location tag holder;

FIG. 8 is a top rear side perspective view of the location tag holder; and,

FIG. 9 is a perspective view of the location tag holder in use. The broken lines extending from the pocket are illustrative of environmental structure forming no part of the claimed design. The broken lines extending adjacent to edges are illustrative of stitching forming no part of the claimed design. The broken lines in FIG. 9 showing a shoe and laces are illustrative of environmental structure forming no part of the claimed design.
